CLAIM

The ornamental design for a conduit adapter, as shown and described.

DESCRIPTION

FIG. 1 is a top perspective view of a conduit adapter showing our new design;

FIG. 2 is a bottom perspective view of the conduit adapter of FIG. 1;

FIG. 3 is a front elevational view of the conduit adapter of FIG. 1, the rear elevational view being identical;

FIG. 4 is a left-side elevational view of the conduit adapter of FIG. 1, the right-side elevational view being identical;

FIG. 5 is a top plan view of the conduit adapter of FIG. 1; FIG. 6 is a bottom plan view of the conduit adapter of FIG. 1; and,

FIG. 7 is a further-angled bottom perspective view of the conduit adapter of FIG. 1.

The evenly spaced broken lines show portions of the conduit adapter that form no part of the claimed design.
